Checks issued during months of.

Inventor
J. Koffend Sr.

By Attorney

UNITED STATES PATENT OFFICE.

JOSEPH KOFFEND, SR., OF APPLETON, WISCONSIN.

SAFETY-CHECK.

1,388,049.

Specification of Letters Patent. Patented Aug. 16, 1921.

Application filed January 28, 1919. Serial No. 273,511.

To all whom it may concern:

Be it known that I, JOSEPH KOFFEND, Sr., a citizen of the United States, residing at Appleton, in the county of Outagamie and State of Wisconsin, have invented certain new and useful Improvements in Safety-Checks; and I do hereby declare the following to be a full, clear, and exact description of the invention, such as will enable others skilled in the art to which it appertains to make and use the same.

My invention relates to improvements in means for detecting forgery of checks and other negotiable instruments.

15 An important object of the invention is to provide checks with peculiar identification marks which will enable the teller at a bank to quickly ascertain if the check is genuine.

20 A further object of the invention is to provide a method of identifying checks, which is simple, easy to remember, and desirable in use.

Other objects and advantages of the invention will be apparent during the course 25 of the following description.

In the accompanying drawings forming a part of this specification, and in which is shown a practical embodiment of my invention,

30 Figure 1 shows a pair of checks illustrating one example of the application of the identifying means.

Fig. 2 is also a view of a pair of checks 35 illustrating another example of the application of the invention,

Fig. 3 is also a view of a pair of checks illustrating still another example of the application of the invention,

40 Fig. 4 is a further adaptation of the invention, and

Fig. 5 is a detail view of the key to the system.

In the practice of my improved check 45 identifying system, the names of the depositors in a bank are divided into a number of classes, which in this particular case includes 11 classes. The depositors in each class are supplied with their respective class number.

50 The class number of each depositor is preferably placed on the check directly beneath the check number, if the arrangement of the printed matter on the check permits. If it is not practicable or permissible to 55 place the class number beneath the check number, the same may be placed in any

desirable suitably conspicuous place, on the face of the check.

In addition to being supplied with a class number, which may be common to a number 60 of depositors, each depositor is also supplied with a guard number. The guard number may be changed from time to time for the purpose of eluding the forgers. In cases where the guard number is under one thousand, the last two figures of the guard number are placed directly behind the class 65 number. The first figure of the guard number is placed in the left hand corner of the diamond at the lower left hand corner of 70 the check.

As illustrated in Figs. 1 to 4 inclusive, each check is provided with a diamond in its lower left hand corner. Each diamond is divided off into two sections. In cases 75 where the guard number is over a thousand, the first two figures of the guard number are placed in the left hand section of the diamond on each of the several checks. In cases where the guard number happens to be over ten thousand, the first two figures of the guard number are placed in the left hand section of the diamond and the remaining three figures of the number are placed directly behind the class number.

85 As a further protective measure, guard months may also be applied to the checks. In cases where a month is to be designated as a guard element, an arbitrary number of months may be agreed upon as the month to 90 be designated on the check. This month may be either before or after the date of the check, thus if it is agreed to employ a month six months in advance of August, the month of March which is six months in advance of 95 August, would be designated on the check. The month is designated by the first letter of the month, namely, "M." The capital letter designating the month is employed only when the month agreed upon is formed 100 of the date of the check. When the month agreed upon is passed the date of the check, the initial of the month may be applied to the check in small letters. The month guard may be applied to the right hand section of 105 the diamond.

If so desired, the sections allotted to the guard number and guard month may be reversed as an additional protective measure from time to time. When protective months 110 are employed, the months having the same first letter may be numbered in the order

of their occurrence. For instance, January may be designated "J1." June may be designated "J2" and July may be designated "J3."

5 In Fig. 1 is illustrated the application of the invention, wherein the class number is shown to be 11. The guard number is shown to be 339. The figure 3 is shown in the left hand section of the diamond on the check 10 and the remaining two figures, namely, 3 and 9 are applied to the check directly behind the class number. In the first check of Fig. 1, the month is shown to be March and is in advance of the date of the check.

15 To indicate that the letter M designates the first of the months of the year beginning with this letter, the numeral 1 is placed in the diamond to the right of the letter.

As indicated in the description of Fig. 1, 20 the fact that the guard month is in advance of the date of the check is indicated by the capital letter "M." In the second check illustrated in Fig. 2, the same class and guard numbers are employed. Instead of employing 25 a month six months in advance of the date of the check, the month six months passed the date of the check is employed, namely, May. The month of May is indicated by the small letter "m" having the numeral 2 therebehind. The numeral 2 indicates that the letter "m" stands for the second month of the year commencing with "M."

30 In Fig. 2, the class number is shown to be number 4 and the guard number, 7593.

As illustrated in Fig. 3, class number 9 is seen to be the class assigned to this particular depositor. The guard number assigned to this particular depositor is seen to 40 be 19,375. The figures 1 and 9 are shown in the left hand section of the diamond at the lower left hand corner of the check. The remaining three figures are shown to be applied to the check directly behind the class 45 number. The month is shown to be January in advance of the date of the check. The month of January is indicated by the fact that the numeral 1 is placed behind the letter "J." The fact that the guard month is 50 in advance of the date of the check is indicated by the fact that the month is indicated by a small "j." In the lower check of Fig.

3, the same class number and guard number is assigned. The month guard, however, is shown to be March in the rear of the date of 55 the check. This is indicated by the small letter "m" and the numeral 1.

In Fig. 4 the several checks are shown to bear the class number 6 and the guard number 97,999. In the case of the two checks 60 illustrated in Fig. 4, the guard month is shown applied to the left hand section of the diamonds. The first two figures of the guard number are shown applied to the right hand section of the diamond in the place formerly 65 occupied by the guard month. In the left hand section of the upper diamond, the month is shown to be April in advance of the check. The fact that the month is April and in advance of the date of the check is 70 indicated by the large letter "A" and the numeral 1 therebehind. In the second check illustrated in Fig. 4, the small letter "d" indicates that the month of December is selected as the guard month. The month of 75 December is in the rear of the date of the check as evidenced by the small letter "d."

In the practical embodiment of my invention, it is not desirable to employ guard numbers lower than 111. Odd figures are 80 preferably used for the guard numbers.

While I have shown and described the preferred embodiment of my invention, it is understood that such other arbitrary key numbers may be employed as will remain within 85 the spirit of the invention and the scope of the appended claim.

Having thus described my invention, what I claim is:—

A negotiable paper bearing a number 90 indicative of the class of the maker and having a guard number, part of which is associated with the class number and part of which is differently located on the face of the paper, and a time character in conjunctive relation with the part of the guard number remotely situated from the class number.

95 In testimony whereof I affix my signature in presence of two witnesses.

JOSEPH KOFFEND, Sr.

Witnesses:

JOHN BOTTENSEK,
FRED N. JANICENOM.
